UNITED STATES PATENT OFFICE.

FRANK E. WILLIAMS, OF ST. LOUIS, MISSOURI, ASSIGNOR TO POLAR ELECTRIC REFRIGERATOR CORPORATION, OF ST. LOUIS, MISSOURI, A CORPORATION OF MISSOURI.

REFRIGERATING APPARATUS.

Application filed August 6, 1925. Serial No. 43,512.

This invention relates to refrigerating apparatus, and more especially to a cooler adapted for cooling efficiently longitudinal compartments, such as the interior of a 5 counter display cabinet of the type used by dealers to display meats and other perishable food. The cooler may be placed on the floor or suspended from any suitable support, and is capable of use for other purposes. Two other applications for modified forms of refrigerating apparatus and one for a refrigerated cabinet have been filed by the same inventor concurrently with this application.

15 Divers objects of this invention and advantages incident thereto will appear in the course of the following description of a preferred embodiment thereof.

In the accompanying drawings forming 20 part of this specification, in which like numbers of reference denote like parts wherever they occur,

Figure 1 is a plan view of the cooler, parts being broken away and others being shown 25 in section;

Figure 2 is a vertical sectional view taken on the line 2—2 in Figure 1;

Figure 3 is a transverse sectional view taken on the line 3—3 in Figure 1; and

30 Figure 4 is a transverse sectional view taken on the line 4—4 in Figure 1.

The cooler comprises a substantially rectangular longitudinal brine tank 1, preferably sheet metal, and having apertures 2 in its top wall 3 corresponding to similar apertures 4 in its bottom wall 5. The apertures 2 and 4 are arranged in transverse rows disposed symmetrically on either side of the middle of the longitudinal dimension of the tank. The apertures 2 and 4 are elongated in the direction of the longitudinal dimension of the tank. Vertical sleeves or walls 6 connect the top and bottom walls of the tank, the open ends of the sleeves 6 being in registration with the apertures 2 and 4, and the sleeve flanges 7 at the said ends are connected to the said top and bottom walls with liquid-tight joints. The ducts or cavities 8 enclosed by the sleeves 6 assist in cooling the 40 surrounding air by promoting the circulation of convection air currents, the air cooled in the ducts 8 descending therein. Nipples 45 9 and 10 are provided in the upper and lower portions, respectively, of the tank to permit the latter to be filled with or emp-

tied of brine, the said nipples normally being closed by caps 11 screw-threaded thereon.

A marginal frame 12 of angle iron rests on the bottom wall 5 of the tank 1, the horizontal flanges 13 of the angle iron frame engaging the said bottom wall, and the vertical flanges 14 of the angle iron frame being disposed on its outer margin and abutting against the inner sides of the lateral 65 walls 15 and 16 and the end walls 17 and 18 of the said tank.

The front lateral wall 15 has an aperture 19 in its upper middle portion to receive the cylindrical end or boss 20 of a vaporizer header 21, arranged transversely in the tank 1. The boss 20 has an opening 22 therethrough to afford access to the interior of the header 21, and the said opening is normally closed by means of a plate or cover 70 23, preferably secured thereto by means of screws 24. Screw-threaded openings 25 and 26 are provided in the cap 23 to make piping connections with a refrigerant circulating system, which connections are not shown 75 since they are old and well known to those skilled in the art. The inner side of the opening 26 may, also, be connected to suitable means for controlling the level of liquid refrigerant in the header 21, such as a float-controlled valve, which means are, also, old and well known, and, therefore, not shown herein.

The boss 20 projects from a shoulder, 27, which abuts against the inner side of the wall 15 and is connected thereto in a 80 fluid-tight manner, being preferably soldered thereto. The upper portion of the header is relatively wide, forming the chamber 28 proper in which the vaporized refrigerant is collected and in which the level 29 of liquid refrigerant is maintained; and the upper portion of the chamber 28 is preferably enclosed by a semi-cylindrical wall portion 30, the opposite sides of which continue 85 downwardly as straight vertical wall portions 31 to the bottom of the chamber 28, and then continue horizontally inward at 32 until they nearly meet. Vertical wall portions 33 depend from the nearly meeting inner ends of the horizontal wall portions 32, and the lower ends of the said portions 33 are connected by a horizontal wall 34, the outer ends of which project beyond the wall portions 33 to form supporting feet 35, 90 which rest on the horizontal flanges 13 of 100 105 110

the frame 12. The thin vertical chamber 36 formed between the wall portions 33 functions as a distributor for the lower portion of the vaporizer.

5 Vertical transverse headers 37 are disposed in opposite ends of the tank 1. The said headers comprise vertical walls 38 and 39, top walls 40, and a bottom wall 41, which projects outwardly beyond the walls 38 and 10 39 to form supporting feet 42, which rest on the horizontal flanges 13 of the frame 12.

Tubes 43 connect the upper portions of the headers 37 with the chamber 28, and tubes 44 connect the lower portions of the 15 headers 37, preferably passing through the distributing chamber 36 in the intermediate header 21. There are three vertical rows of such tubes, each row comprising superposed lower tubes 44 and superposed upper tubes 43. One of the rows passes between the front wall 15 and the sleeves 6 adjacent thereto; another intermediate the pair of sleeves 6 comprising a transverse row; and the third is interposed between the rear wall 20 25 16 and the sleeves 6 adjacent thereto. The inner walls 39 of end headers 37, and the wall portions 31 and 33 of intermediate header 21, have exterior bosses 45 thereon, provided with openings 46 therethrough to 30 receive the pipes 43 and 44 in a liquid-tight manner, the pipes being preferably soldered therein. That portion of each of the tubes 44 disposed within the chamber 36 is apertured at 47 on its upper side to effect communication between the chamber 36 and the 35 interior of the tubes 44.

Liquid refrigerant, preferably sulphur dioxide, is supplied to the chamber 28 of the header 21 through the opening 26 from any 40 suitable compressing or liquefying apparatus included in the refrigerant circulating system. The liquid refrigerant flows into the chamber 36 and through pipes 43 and 44 into the interior of the hollow end headers 45 37. The liquid boils in the evaporator comprising the said headers and pipes, absorbing heat from the surrounding brine in the sheet metal tank 1. The vapor arising in the pipes and headers eventually reaches the 50 vapor space in the upper portion of the chamber 28, from whence it is drawn off by the suction of the compressor included in the refrigerant circulating system. It is worthy of note that the bubbles of vapor 55 arising through each of the openings 47 are deflected from a straight upward course by the obstruction encountered in the next higher pipe thereabove, so that the ascending bubbles can not obstruct the openings of the higher pipes and interfere with the flow of liquid refrigerant thereto. If the pipes 44 did not extend through the chamber 36, but terminated in open ends thereat, 60 manifestly bubbles ascending through the chamber 36 would obstruct such end open-

ings which they encountered in their passage. The term brine as used herein is to be construed broadly as including any suitable anti-freezing solution, such as alcohol, sodium chloride, calcium chloride and the like, the latter solution being preferred. The cap 11 of nipple 9 is preferably provided with a vent opening 48 in the top thereof to allow air to enter into or pass out of the tank to compensate for the contraction 75 or expansion of the brine therein with variation of temperature.

One of the merits of the present invention resides in the fact that the configuration of the vaporizer in the tank is such that each 80 sleeve 6 is entirely surrounded by respective portions of the vaporizer. This distribution of the several portions of the vaporizer in the tank contributes to an even cooling of all sides of the sleeves 6, as well as of the sides 85 of the tank; supplementing the function of the circulating brine in this respect.

Having thus fully described this invention, I hereby reserve the benefit of all changes in form, arrangement, order, or use of parts, 90 as it is evident that many minor changes may be made therein without departing from the spirit of this invention or the scope of the following claims.

I claim:

1. A horizontally elongated vaporizer for a refrigerant comprising a vertically transversely disposed intermediate hollow distributing header having the upper portion of its interior relatively wide and the lower portion relatively constricted, a pair of vertical transverse hollow headers disposed respectively at opposite ends of the vaporizer, and a transverse series of vertical rows of superposed horizontal pipes directly connecting the end headers with the intermediate header.

2. In a refrigerating apparatus, a horizontally elongated substantially rectangular brine tank having a transverse row of vertical passages therethrough partitioned from the tank interior, a pair of headers disposed in the tank interior on opposite sides of the said row, and pipes in the tank intermediate the said passages and connecting the said headers.

3. In a refrigerating apparatus, a horizontally elongated substantially rectangular brine tank having a pair of transverse rows of vertical passages therethrough partitioned from the tank interior, each row being disposed in a respective longitudinal end portion of the tank; a vaporizer distributing header vertically transversely disposed in the tank interior intermediately of the said rows; a pair of vertical transverse headers disposed respectively at opposite ends of the vaporizer beyond the row of passages thereat; and a series of vertical rows of superposed horizontal pipes connecting the end

headers with the intermediate header, each of the intermediate rows of pipes passing between two respective vertical adjacent passages of a row, and each of the outer rows of pipes passing between the adjacent side of the tank and the adjacent outer passage of a row.

4. In a refrigerating apparatus, a substantially rectangular brine tank having a marginal frame of angle iron on the floor thereof, a plurality of vaporizer headers resting on the said frame and disposed in proper spaced relation to the tank thereby, and pipes connecting the said headers.

15 5. A vaporizer for a refrigerant comprising an intermediate hollow distributing header, a pair of hollow end headers, and pipes extending from one end header through the intermediate header to the other end header, that portion of each of the pipes within the intermediate header being provided with a lateral opening to effect communication with the interior of the intermediate header.

6. A refrigerating apparatus comprising a 25 tank, an intermediate hollow header positioned within the same, said header defining a vapor-receiving chamber at its upper end and developing at its lower end into a relatively thin and wide vertically disposed distributing chamber, end headers disposed respectively on opposite sides of said intermediate header and pipes connecting the end headers with said intermediate header.

7. A vaporizer for a refrigerant comprising 35 an intermediate hollow distributing header, a pair of hollow end headers and a plurality of pipes extending from the end header through the intermediate header to the other end header, that portion of each of 40 the pipes within the intermediate header being provided with an upwardly directed opening to effect communication with the interior of the intermediate header.

In testimony whereof I hereunto affix my 45 signature.

FRANK E. WILLIAMS.
